UNITED STATES PATENT OFFICE.

JAMES O. BANE, OF ST. PAUL, MINNESOTA.

SPRING-COUNTERBALANCE FOR PUMPS.

1,323,568.

Specification of Letters Patent.

Patented Dec. 2, 1919.

Application filed May 23, 1918. Serial No. 236,246.

To all whom it may concern:

Be it known that I, JAMES O. BANE, a citizen of the United States, residing at St. Paul, in the county of Ramsey and State of Minnesota, have invented certain new and useful Improvements in Spring-Counterbalances for Pumps, of which the following is a specification.

This invention relates to means for counterbalancing the plunger rod of a pump and the weight of the water raised thereby, to render the operation of pumping easier and more economical, and it consists in the construction and combination of parts forming 15 a spring counterbalance for pumps herein-after more fully described, and particularly stated in the claims, reference being had to the accompanying drawings, in which:

Figure I, is a side elevation of a pump 20 with my invention attached to it.

Fig. II, is an under side view of the baseplate and portions of some adjacent parts.

Fig. III, is a vertical section at line x, Fig. II.

25 Fig. IV, is a top view of one half of the lower plate.

Numeral 5 represents the body of a common hand pump; 6 the plunger rod—commonly called the pump rod; 7 the operating 30 handle; 8 the pitman on which the handle is pivoted, and 9, a bracket extending up from the pump cap 10, to serve as a guide for the rod 7.

The baseplate 11, of my spring counterbalance attachment, rests on top of the bracket 9. The jaws 12, are bound together by a screw bolt 13, to firmly grip the rod 7 above the base plate 11.

The lower levers 14, each of which is 40 hinged on a pivot bar 15, of the plate 11, so as to swing vertically, is provided with lateral arms 16, on which, and the body of the lever, a spring 17, stands. The top levers 18, hinged at 19 to the jaws 12, and provided 45 with lateral arms 30, to rest on the springs 17, are operatively connected at their outer ends with the lower levers 14, by turnbuckles 20, whereby any desired tension may be given the springs 17.

50 The jaws 12 may be shaped to engage either round, flat or square rods when forced thereon by the binding bolts 13. The baseplate 11, comprises a pair of half plates which are duplicates in size and shape, being 55 cast from the same pattern; the shape being particularly shown in Fig. IV.

Each half plate has at one end a tang 21, and near the other end a slot to receive the tang of its mate when the halves are pushed together edgewise, and is provided with 60 slots 22, which register when together to receive bolts 23, by which the two half plates are rigidly bound together to form a baseplate 11, to act as a unit when in service. The side bars 24, and the tangs 21, of both 65 halves of the plate rest on the bracket 9, so that pressure on the hinge bars 15, holds both of the tangs down against the prying action of pressure on their own opposite ends, further increasing the rigidity of the 70 half plate joint.

The open side of each half plate permits them to be placed around a pump rod before they are secured together. The slots 22, permit the said halves to be adjusted to pump 75 rods of different sizes, and the bolts 23, bind them when adjusted. A little play should be allowed at the sides of the rod, the inner faces of the side bars 24, being shaped to fit as required, either round, flat or square rods. A 80 thick washer 25, secured by each bolt 23, has a nick in one edge to receive a rib 26, which is cast on the inner end of each lever 14, to keep the latter in a vertical plane with the pump rod, whatever the adjustment may be 85 to fit its thickness.

This whole device is composed of pairs of parts that are duplicates, so that a single pattern serves for the two parts of each pair, rendering it economical in manufacture and 90 easily understood. The facilities for quick attachment to different pumps, and for quick adjustment to their respective loads adapts this device to be applied and practically operated by a traveling salesman to demonstrate its merit on the pump of any customer. 95

I claim:

1. In a spring counterbalance for pumps, a baseplate comprising two duplicate, transversely slotted half plates adapted to freely 100 engage pump rods of different sizes, and to rest upon the top portion of a pump; bolts to engage the slots, and a notched washer on each bolt; a pair of levers hinged to the baseplate opposite to each other, and having 105 laterally projecting arms, each lever having a rib on its hinge end to engage the notch in one of the said washers; a pair of jaws and bolts to secure them to a pump rod above the baseplate; a pair of levers hinged to the said 110 jaws over the first named levers, and having laterally projecting arms; a pair of turn-

buckles connecting the outer ends of the two pairs of levers, and a pair of springs located between the arms of the upper and lower levers.

- 5 2. In a spring counterbalance for pumps, a baseplate comprising two similar half plates, each half having a slot in its under side and a hinge bar at one end, a tang at the other end and a slot between the said 10 slot and tang to receive a pump rod; a slot

at each end side of the said notch, and bolts to enter the slots in the two halves and rigidly hold them together.

In testimony whereof I affix my signature in the presence of two witnesses.

JAMES O. BANE.
